(57) **CLAIM**

The ornamental design for a lid of container for packaging, as shown and described.

DESCRIPTION

1. Lid of container for packaging

1.1 : Perspective view 1

1.2 : Perspective view 2

1.3 : Front

1.4 : Top

1.5 : Bottom

1.6 : Left

1.7 : Right

1.8 : Back

1.9 : Cross-sectional

1.10 : Cross-sectional

1.11 : Exploded perspective view

1.12 : Top view showing the rotated top lid

Fig. 1.9 is a sectional view taken along the line tilted at an angle of 20 degrees of fig. 1.4 with respect to the horizontal line; fig. 1.10 is a sectional view taken horizontally at the center of fig. 1.4.
